CLAIM

The ornamental design for an electronic display unit, as shown and described.

DESCRIPTION

1. Electronic display unit

1.1 : Perspective

1.2 : Rear perspective view

1.3 : Front

1.4 : Back

1.5 : Left

1.6 : Right

1.7 : Top

1.8 : Bottom

1.9 : Additional rear perspective view

Reproduction 1.9 shows the electronic display unit within an alternate broken line environment of use assembled with

(Continued)

other display units; the broken lines indicate portions of the article and environmental structure forming no part of the claimed design.

1 Claim, 9 Drawing Sheets
